UNITED STATES PATENT OFFICE.

WILLIAM T. BURGESS, OF CROWVILLE, LOUISIANA.

KEYLESS PADLOCK.

1,149,022.

Specification of Letters Patent.

Patented Aug. 3, 1915.

Application filed April 30, 1915. Serial No. 25,009.

To all whom it may concern:

Be it known that I, WILLIAM T. BURGESS, a citizen of the United States, residing at Crowville, in the parish of Franklin and 5 State of Louisiana, have invented certain new and useful Improvements in Keyless Padlocks; and I do hereby declare the following to be a full, clear, and exact description of the invention, such as will enable 10 others skilled in the art to which it appertains to make and use the same.

The invention relates to improvements in locks.

The object of the present invention is to 15 improve the construction of locks and to provide a keyless pad lock of simple and comparatively inexpensive construction equipped with a pivoted shackle and locking means engaging the shackle and releasable by practically concealed operating means.

With these and other objects in view the invention consists in the construction and 20 novel combination and arrangement of parts hereinafter fully described, illustrated in the accompanying drawings and pointed out in the claims hereto appended, it being understood that various changes in the form, proportion and minor details of construction may be resorted to without departing from 25 the spirit or sacrificing any of the advantages of the invention.

In the drawing Figure 1 is an elevation of a keyless pad lock constructed in accordance with this invention, Fig. 2 is a plan 30 view of the same, Fig. 3 is a vertical longitudinal sectional view of the pad lock illustrating the arrangement of the parts when the shackle is locked, Fig. 4 is horizontal sectional view on the line $a-a$ of Fig. 3. Fig. 5 is a side elevation of a keyless pad lock showing another form of the invention, Fig. 6 is a plan view of the same, Fig. 7 is a 35 vertical longitudinal sectional view of the pad lock shown in Fig. 5, the parts being locked, Fig. 8 is a horizontal sectional view on the line $8-8$ of Fig. 7.

Like numerals of reference designate corresponding parts in all the figures of the drawing.

50 In the accompanying drawing in which is illustrated the preferred embodiment of the invention, 1 designates a lock casing provided with a face plate 2 secured by rivets 3 or other suitable fastening devices to the body of the casing which is provided at the top with front and rear openings 4 and 5

for a pivoted shackle 6. The shackle 6 is pivoted by a transverse pin or rivet 7 located near the rear end 8 of the shackle which projects slightly beyond the pivot 7 to form a 60 heel. The heel or end 8 is engaged by a spring 9 secured at one end 10 by a rivet or other suitable fastening device to the casing and bearing at an intermediate point against the stud 11 and having its free end engaging the said heel or end 8 of the shackle and adapted to swing the latter open automatically as soon as the shackle is released by a catch 12. The casing is provided with a chamber 13 to receive the lock mechanism 70 and the said chamber has an inclined front wall 14 to which is secured the catch 12. The catch 12 consists of a spring riveted or otherwise fastened at its lower end 15 to the said inclined front wall 14 and provided at 75 its upper free end with a head 16 beveled at the front and shouldered at the inner portion to engage a corresponding head or catch 17 of the free end of the shackle 6. The resilient catch is adapted to engage the head 80 or catch of the shackle 6 automatically when the latter is moved to its closed position against the action of the spring 9. The front wall 14 is intersected by a passage 18 extending upwardly from the bottom of the 85 lock and receiving a slidable operating bar or member 19 provided at its inner or upper end with a wedge or cam head 20 having a rounded inner face which is arranged to engage a concaved face 21 of an intermediate 90 enlargement 22 of the catch 12 whereby when the slidable operating member is moved inwardly it will force the catch backwardly out of engagement with the shackle and permit the same to be automatically opened by 95 the spring 9. The front plate is provided at the center with a key hole 22' which is designed to mislead a person not familiar with the construction of the keyless pad lock.

In Figs. 5 to 8 inclusive of the drawing is 100 illustrated another form of the invention in which the lock casing 23 is in the form of a man's head but it may be of any other ornamental configuration. The casing 23 is provided with a chamber 24 having a front wall 105 intersected by a passage 25 extending upwardly and inwardly at an inclination from the bottom of the nose portion 26 and receiving a slidable downwardly tapered operating bar or member 27 which has a tapered or 110 wedge shaped upper end 28 adapted to engage a catch 29. The downwardly tapered

operating bar or member 27 and passage 25 serve to limit the outward or downward movement of the said bar or member, the downward or outward movement of the bar or member 19 being limited by the head thereof engaging the inner wall at the upper end of the passage 18. Any other suitable means, however, may be employed for limiting the outward movement of either of the operating bars or members. The catch 29 consists of a spring riveted or otherwise secured at its lower or inner portion to the front wall of the casing and provided at its upper end with a catch 30 for engaging a catch 31 of a shackle 32 pivoted adjacent to its rear end 33 by a pin 34 or other suitable fastening device. The inner or rear end 33 constitutes a heel and is engaged by a spring 35 having its free end bearing against the shackle and secured at its other end 36 and bearing at an intermediate point against the stud 37. The casing 23 is provided with a key hole 38 which is preferably arranged to present the form of an ear.

It will be seen that the keyless pad lock is exceedingly simple and inexpensive in construction and that a person not familiar with the construction of the pad lock will find considerable difficulty in opening the same. Also it will be apparent that a person familiar with the construction of the keyless pad lock may quickly operate the latter to release the shackle so that the lock may be quickly applied in position for engagement with the part to be locked.

What is claimed is:—

1. A lock of the class described including a casing having a chamber and provided with a passage intersecting one of the walls 40 of the chamber, a pivoted shackle, a catch secured within the chamber adjacent to the said passage and arranged to engage the

shackle, and an operating bar or member slideable in the passage and arranged to move the catch out of engagement with the shackle to release the latter, said operating bar or member being concealed within the casing and having its outer end arranged substantially flush with the adjacent portion of the exterior surface of the casing. 50

2. A lock of the class described including a casing provided with a passage terminating at one end at the exterior of the casing, a pivoted shackle, a catch mounted within the casing and arranged to engage the pivoted shackle, and an operating bar or member 55 slideable in the passage and having its outer end arranged substantially flush with the adjacent portion of the exterior surface of the casing, said operating bar or member being provided at its inner end with a substantially wedge-shape portion arranged to engage the catch for forcing the latter out of engagement with the shackle. 60

3. A lock of the class described including 65 a casing, a pivoted shackle, a resilient catch arranged to engage the shackle and locked in its closed position, said catch being provided at an intermediate point with a tapered enlargement presenting a concaved 70 face and an operating bar or member slideable in the casing and provided with a wedge or a cam head arranged to engage the enlargement to force the catch out of engagement with the shackle, said bar or member 75 having one of its ends arranged for exterior operation.

In testimony whereof I affix my signature in presence of two witnesses.

WILLIAM T. BURGESS.
